PULLEY

Ernest J. Ortiz, Jamesburg, N. J.

Application October 11, 1954, Serial No. 32,610

Term of patent 14 years

(Cl. D41—1)

Fig. 1

Fig. 3

Fig. 1 is a perspective view of a pulley handle showing my new design with the portion thereof shown disposed in its operative position,

Fig. 2 is a top plan view thereof, and

Fig. 3 is a view corresponding with Fig. 1 but showing the handle disposed in an inoperative position.

I claim:

The ornamental design for a pulley, as shown.
